UNITED STATES PATENT OFFICE.

CHARLES CROWLEY, OF PERTH, AUSTRALIA.

PNEUMATIC NON-SINKABLE SHIELD FOR BOATS.

1,170,420.

Specification of Letters Patent. Patented Feb. 1, 1916.

Application filed January 3, 1914. Serial No. 810,192.

To all whom it may concern:

Be it known that I, CHARLES CROWLEY, a subject of the King of Great Britain, and residing at 177 Fitzgerald street, Perth, Western Australia, Commonwealth of Australia, have invented certain new and useful Improvements in Pneumatic Non-Sinkable Shields for Boats, of which the following is a specification.

10 The object of this invention is to provide boats with a pneumatic non-sinkable shield or outer hollow wall, said outer wall being in the nature and form of an attachment to said boat.

15 In this specification the word "boat" is intended to comprise and mean boats, ships and all other water borne vessels of any kind or nature.

20 The invention is particularly valuable for use with life saving boats for the purpose of rendering them safe and free from being swamped or sunk. Furthermore the use of this invention increases the buoyancy and consequently increases the carrying capacity 25 of the boat and its money earning value.

25 The invention is adapted to be built integrally with the boat when latter is being made or it may be attached to any existing boat.

30 The invention essentially consists and resides in building boats or other water borne vessels with an outer surrounding air chamber and with a resultant and intervening water space or cavity between said air chamber and the actual hull of the boat.

35 The shield surrounds the boat and follows or approximates the shape and conformation thereof and the resultant and intervening space which exists between the hull of the boat and the shield communicates with and is open and free to the outer water of the lake, river or ocean as the case may be.

40 Reference will now be made to the attached drawings in which is illustrated the use of my invention in connection with a boat and in said drawings Figure 1 is a transverse sectional view and Fig. 2 is a longitudinal sectional view on line $x-x$ of Fig. 1.

45 In said drawings a is the hull or shell of the boat as shown in broken lines and to same is riveted or otherwise secured the ribs b made of steel or iron plates of any approved section. These ribs b are placed vertically as shown in Fig. 2. To these ribs are riveted or otherwise secured the hollow wall

which comprises the inner and outer shells $c-d$ and which provides the pneumatic or air chamber or shield for the boat. This wall surrounds the boat as seen clearly in Fig. 2 and is closed or sealed on all sides and said wall in section is preferably of a taper or wedge shape as shown in Fig. 1. The space as e which exists between the boat hull a and the wall $c-d$ acts as the water space and as previously stated communicates with the outer water of the ocean as denoted by the letter m and as seen in Fig. 1. This water space may extend upwardly to a line level with the top of the chamber $c-d$ or to the main deck as f of the boat. This hollow wall $c-d$ is divided up into separate sealed tight cellular compartments as g both in a longitudinal vertical direction and which method of construction allows of any one compartment being injured or punctured without endangering any neighboring compartment or the wall $c-d$ as a whole. The partitions which form the cellular compartments g connect the shells $c-d$ and brace them to one another. The water in the space e communicates with the water of the ocean m by way of the open mouthed passages j placed in proximity to the keel of the boat or water openings may be placed at other approved points of the wall $c-d$.

45 It will be seen that by means of this invention I obtain a water space surrounding the boat and also an outer pneumatic wall provided by the sealed chamber $c-d$.

50 When the invention is employed with small boats such as rowing or sailing boats the wall $c-d$ may be removably connected to the boat by plates or straps while the keel edges of the boat and said wall may be hingedly connected to each other.

55 What I claim as my invention and desire to secure by Letters Patent is:—

1. The combination with a conventional boat hull of an inclosing, structurally independent, continuous, hollow, air-filled wall comprising as an entirety a pair of spaced shells connected and braced to one another, the said shells extending throughout the longitudinal and vertical depth of said hull and each conforming to the longitudinal and vertical outline thereof, and vertical plates arranged at suitable intervals and fixedly connecting the hull and the wall and also definitely spacing the latter throughout its extent from the former, the wall being

open at its lower end adjoining the keel of the boat to provide open communication between the space intermediate the boat and the wall and the water in which the boat is borne.

2. The combination with a conventional boat hull of an inclosing, structurally independent, continuous, hollow, air-filled wall comprising as an entirety a pair of spaced shells, and means connecting said shells and bracing them to one another and dividing the space between said shells into compartments or cells, the said shells extending throughout the longitudinal and vertical depth of said hull and each conforming to the longitudinal and vertical outline there-

of, and vertical plates arranged at suitable intervals and fixedly connecting the hull and the wall and also definitely spacing the latter throughout its extent from the former, the wall being open at its lower end adjoining the keel of the boat to provide open communication between the space intermediate the boat and the wall and the water in which the boat is borne. 20

In testimony whereof I have hereunto set my hand in presence of two subscribing witnesses.

CHARLES CROWLEY.
